[57] CLAIM

The ornamental design for a handle end of a food serving utensil, as shown and described.

DESCRIPTION

FIG. 1 is a prospective view of a handle end of a food serving utensil showing my new design;

FIG. 2 is a front elevation view thereof;

FIG. 3 is a right side elevation view thereof;

FIG. 4 is a top plan view thereof;

FIG. 5 is a bottom plan view thereof;

FIG. 6 is a left side elevation view thereof; and,

FIG. 7 is a rear elevation view thereof.

The broken lines showing the utensil are for illustrative purposes only and form no part of the claimed design.
